RAILROAD CAR TRUCK

Filed Feb. 12, 1924

2 Sheets-Sheet 2

Inventor:
Herman C. Priebe
By G. A. Cragg Atty.

UNITED STATES PATENT OFFICE.

HERMAN C. PRIEBE, OF BLUE ISLAND, ILLINOIS.

RAILROAD-CAR TRUCK.

Application filed February 12, 1924. Serial No. 692,369.

To all whom it may concern:

Be it known that I, HERMAN C. PRIEBE, a citizen of the United States, residing at Blue Island, in the county of Cook and the State of Illinois, have invented a certain new and useful Improvement in Railroad-Car Trucks, of which the following is a full, clear, concise, and exact description.

My invention relates to trucks for rail-
10 road cars and resides in the employment of U bolts in the region of the truck bolsters and the side frames of the trucks, these U bolts taking part in defining the positions of the bolster springs and the locations for
15 the bolster ends. In carrying out the invention, the bolster guide portions are preferably formed with longitudinal bores through which the sides of the U bolts pass, whereby the U bolts are enabled to perform
20 their functions without altering the general dimensions of the side frame and without interfering with the usual locations of the brake hangers. The invention also resides in an improved arrangement of the truck
25 bolster springs and the forking of the bolster ends into three branches between which the upright bolster guide bars pass, or otherwise forming two passages in each end of the bolster to receive these guide bars.
30 The invention, in all of its characteristics, will be more fully explained in connection with the accompanying drawings in which Fig. 1 is a side view of a car truck made in accordance with the preferred em-
35 bodiment of the invention; Fig. 2 is a view taken from beneath the truck as shown in Fig. 1; parts being shown in section and parts being removed; Fig. 3 is a perspective view of a block which is employed between
40 the bases of the U bolts and the lower arch bars in the structure shown in Figs. 1 and 2; Fig. 4 is a sectional view of a modification, taken on line 4—4 of Fig. 6; Fig. 5 is a sectional view on line 5—5 of Fig. 6; Fig.
45 6 is a sectional view on line 6—6 of Fig. 4; Fig. 7 is a sectional view on line 7—7 of Fig. 6; and Fig. 8 is a sectional view on line 8—8 of Fig. 6.

Like parts are indicated by similar characters of reference throughout the different figures.

The truck side frame illustrated in Figs. 1 to 3 includes an upper arch bar 1, a lower arch bar 2, and the bolster guide bars 3 and 4, which depend from the upper arch bar and do not extend across the space be-

tween the arch bars in the structure shown, though the invention is not to be thus limited. Each side of the truck has such a side frame. As the drawing only illustrates the complete construction at one side of the truck, the construction of but one side will be alone described, it being understood that such description pertains to the construction at each side. 65

Upright truck bolster supporting springs 5, 6 and 7 are located between the arch bars and in the general plane thereof. In the construction of Fig. 1 these springs are seated directly upon the lower arch bar, and the upright U bolt 8 which serves to define the positions of springs 5 and 7 has its base below the lower arch bar and its sides passing through both of the arch bars with which the bolt is held in assembly by means of its nuts 9 threaded upon the upper ends of the bolt sides. The bolster guide bars 3, 4 are formed with vertical bores which are coaxial with the bores of the upright springs 5, 7. The sides of the U bolt are 75 passed through aligned bores of the guide bars and said springs, the U bolt being in the general plane of the truck side frame. The truck bolster 10 extends between the sides of the U bolt and is supported by the 80 springs 5, 6 and 7 and has wings 11 at its bottom through which the sides of the bolt pass, these wings being interposed between the bolster guide bars and springs 5 and 7 underlying these guide bars. The intermediate 85 upright truck bolster supporting spring 6 and its associate springs 5, 7 are so related that their axes and the axes of the sides of the U bolt are in a common vertical plane that also includes the corre- 90 sponding side frame. The bolster is guided in its movements by the side portions thereof, which are above the bolster wings 11, and the contiguous bolster guide portions. The sides of the U bolt and the 95 wings 11 of the bolster also take part in guiding the bolster. As the sides of the U bolt pass through the bolster supporting guides, the employment of the U bolt does not interfere with the normal location of 100 the brake hangers 12, 13 which are carried by the supports 14, 15 that are preferably cast integrally with the bolster guide bars 3, 4. These supports form the subject of another application, Serial No. 692,371, filed February 12, 1924. The brake members 16 and 17 are carried at the lower ends 110

of the brake hangers to be in normal relation with the wheels 18, 19 that are disposed at the ends of the contiguous side frame and whose axles 20 engage the bearings 21 which are housed within the journal boxes 22 suitably assembled with the side frame.

In the structure shown in Figs. 1 and 2 the sides of the U bolt pass through both 10 arch bars and the base of the U bolt underlying the lower arch bar. When this construction is employed a block 23 is preferably interposed between the U bolt base and the bottom arch bar, there being a groove 15 24 in the bottom of this block and extending longitudinally of the side frame, and receiving the base of the U bolt.

In the modified construction shown most clearly in Fig. 6, the base of the U bolt is 20 located between the arch bars and the sides of the U bolt pass upwardly through the seat 25 for the bolster supporting springs, this seat being supported upon the lower arch bar.

25 The brake hangers 12, 13 in the structure of Fig. 6, are carried by the supports 14', 15' that are integrally cast with the upward continuations 25', 25' of the spring seat 25. In the structure of Fig. 6 the truck bolster 30 not only extends between the sides of the U bolt and the bolster guide bars 3', 4' that are also integrally formed with the spring seat 25, but has side continuations 10', 10² through which the sides of the U 35 bolt pass and which are sufficiently spaced apart from the truck bolster portion that extends between the sides of the U bolt to receive the truck bolster guides 3', 4', that are in direct guiding relation with this 40 middle portion of the truck bolster, and also the truck bolster guide bars 3², 4² which are carried by and depend from the upper arch bar and are in direct guiding relation with the truck bolster end portions 10', 10³.

45 As illustrated in Fig. 6, the truck bolster guide bars 3', 4' that are carried by the lower arch bar partially embrace the truck bolster guide bars 3², 4² so that the guide bars not only take part in guiding the truck 50 bolster in its upright movements but also serve as structural parts of the side frame.

Referring again to the construction shown in Figs. 1, 2 and 3, the means there shown for assembling the journal boxes with the 55 contiguous side frame includes two frame members in the form of U bolts, whose bases 26 are received in the grooves 27 that extend transversely through the block 23 and intersect the longitudinal groove 24 in 60 this block. The grooves 27 are just sufficiently deeper than the groove 24 to enable the U bolt bases 26 to be held tightly by the base of the U bolt 8 between this U bolt base and the block 23. The symmetrically related pairs of the U bolt sides

28, 29 continue from their U bolt bases longitudinal of the contiguous side frame of the truck and beneath the same, and beneath the journal boxes 22. One of the sides 28 of each of these underlying U bolts is bent 70

near its end at an angle and passes upwardly through the ears 30 upon the side of the adjacent journal box 22 which is nearer the truck bolster and also through the approached ends of the two arch bars that 75 overlie the journal boxes. The complementary U bolt side 29 of each underlying U bolt is continued below its associate journal box to the opposite side thereof and is bent to pass upwardly through the ears 31 80

upon this side of such journal box and thence through the approached ends of the arch bars. The bolt nuts 32 are screwed 85 upon the upper ends of the upright portions of the U bolt sides 28, 29 to clamp the arch bars together and also to clamp the journal boxes between the arch bars and the contiguous U bolt sides 28, 29 that thus are in supporting relation to the journal boxes.

In the construction described in connection 90 with Figs. 1 to 3 inclusive, it is to be observed that the symmetrically related underlying U bolts that thus take part in assembling the ends of the two arch bars and the journal boxes are so shaped and disposed 95

as also to constitute lower members of the corresponding side frame. The upwardly bent end portions of these underlying U 100 bolts are spaced apart, longitudinally of the contiguous side frame, as has been said in other words, to define with the ends of the arch bars and the horizontal portions of these U bolt sides, spaces to receive the journal boxes.

105 In the structure shown in Figs. 1 to 3 inclusive, each side frame is further assembled with the truck bolster by a link 33 that engages the T-shaped lug 34 at the mid portion of the bolster and the hook 35 upon the corresponding side frame. In the 110 structure shown in Figs. 4 to 8 links 33' of another form are otherwise employed to assemble the side frames and mid portions of the truck bolsters. The employment of the links 33 and 33' form the subject matter of another application, Serial No. 692,370, filed February 12, 1924.

115 It is obvious that changes may be made without departing from the spirit of my invention.

Having thus described my invention I claim as new and desire to secure by Letters Patent the following:

1. A car truck including the side frames thereof, each having two upright bolster guide bars; a truck bolster extending between said frames and forked into three branches at each end, said guide bars being received between the branches of the bolster.

2. A car truck including the side frames thereof, each having two upright bolster guide bars; a truck bolster extending between said frames and formed with two 5 passages at each end and that receive said guide bars.
3. A car truck including a side frame; an upright U bolt assembled with said side frame and having its base in the plane thereof; and a truck bolster between the sides of the U bolt.
4. A car truck including a side frame; an upright U bolt assembled with said side frame and having its base in the plane thereof; a truck bolster between the sides of the U bolt; and truck bolster guide bars carried by the side frame and through which the sides of the U bolt pass.
5. A car truck including a side frame; an upright U bolt assembled with said side frame and having its base in the plane thereof; a truck bolster between the sides of the U bolt; and truck bolster supporting springs through which the sides of the U bolt pass.
6. A car truck including a side frame; an upright U bolt assembled with said side frame and having its base in the plane thereof; a truck bolster between the sides of the U bolt; truck bolster guide bars carried by the side frame and through which the sides of the U bolt pass; and truck bolster supporting springs through which the sides of the U bolt pass.
7. A car truck including a side frame; an upright U bolt assembled with said side frame and having its base in the plane thereof and underlying the bottom of the frame; and a seating block between the base of the U bolt and the bottom of the frame and having a groove in its bottom extending longitudinally of the truck and receiving the base of the U bolt.
8. A car truck including a side frame; an upright U bolt assembled with said side frame and having its base in the plane thereof and underlying the bottom of the frame; and a seating block between the base of the U bolt and the bottom of the frame; a truck bolster between the sides of the U bolt; and truck bolster guide bars carried by the side frame and through which the sides of the U bolt pass; and truck bolster supporting springs through which the sides of the U bolt pass.
9. A car truck including a side frame; an upright U bolt assembled with said side frame; and a truck bolster between the sides of the U bolt.
10. A car truck including a side frame; an upright U bolt assembled with said side frame; a truck bolster between the sides of the U bolt; and truck bolster guide bars carried by the side frame and through which the sides of the U bolt pass.
11. A car truck including a side frame; an upright U bolt assembled with said side frame; a truck bolster between the sides of the U bolt; and truck bolster supporting springs through which the sides of the U bolt pass.
12. A car truck including a side frame; an upright U bolt assembled with said side frame; a truck bolster between the sides of the U bolt; truck bolster guide bars carried by the side frame and through which the sides of the U bolt pass; and truck bolster supporting springs through which the sides of the U bolt pass.
13. A car truck including a side frame; an upright U bolt assembled with said side frame; and a seating block between the base of the U bolt and the bottom of the frame and having a groove in its bottom extending longitudinally of the truck and receiving the base of the U bolt.
14. A car truck including a side frame; an upright U bolt assembled with said side frame; and a seating block between the base of the U bolt and the bottom of the frame.
15. A car truck including its side frames; a bolster; truck bolster guide bars upon the frames; and U bolts completing the assembly of the guide bars and side frames, said U bolts having their sides extending along the guide bars, the ends of these sides being clamped into engagement with the side frames.

In witness whereof, I hereunto subscribe my name.

HERMAN C. PRIEBE.
